UNITED STATES PATENT OFFICE

140,591

DESIGN FOR AN EXCAVATING MACHINE FRAME

Hubert Hollmann, River Forest, Ill., and William G. Van Voorhis, Columbus, Ohio, assignors to The Buckeye Traction Ditcher Company, Findlay, Ohio, a corporation of Ohio

Application December 4, 1944, Serial No. 116,703

Term of patent 14 years

(Cl. D14—3)

To all whom it may concern:

Be it known that we, Hubert Hollmann, a citizen of the United States and resident of River Forest, Cook County, Illinois, and William G. Van Voorhis, a citizen of the United States and resident of Columbus, Franklin County, Ohio, have invented a new, original, and ornamental Design for an Excavating Machine Frame, of which the following is a specification, reference being had to the accompanying drawings, forming a part thereof.

In the drawings:

Figure 1 is a perspective view of the front end of the excavating machine frame showing our new design; and

Figure 2 is a bottom plan view of the frame.

This application constitutes a continuation-in-part of our application Serial Number D-110,630, filed July 8, 1943.

We claim:

The ornamental design for an excavating machine frame, as shown.

HUBERT HOLLMANN.

WILLIAM G. VAN VOORHIS.
